UNITED STATES PATENT OFFICE.

JAMES G. CAMP, OF SACRAMENTO, CALIFORNIA.

HYDROCARBON-BURNER.

SPECIFICATION forming part of Letters Patent No. 760,729, dated May 24, 1904.

Application filed November 24, 1903. Serial No. 182,520. (No model.)

To all whom it may concern:

Be it known that I, JAMES G. CAMP, of Sacramento, in the county of Sacramento and State of California, have invented a certain new and useful Improvement in Hydrocarbon-Burners, of which improvement the following is a specification.

The object of my invention is to provide an apparatus for burning liquid fuel which shall be simple and inexpensive in its construction, of ready applicability in connection with furnaces of different forms, and capable of conducting the combustion of heavy oil under low pressure, and with the production of a soft white flame which is practically smokeless and is devoid of the cutting action of that of high-pressure burners.

The improvement claimed is hereinafter fully set forth.

In the accompanying drawings, Figure 1 is a view, partly in elevation and partly in longitudinal section, of a burner, illustrating an embodiment of my invention; Fig. 2, an end view as seen from the right; Fig. 3, a horizontal section through the outlet portion of the fuel-discharge pipe, and Fig. 4 a transverse section through the same on the line *a a* of Fig. 1.

In the practice of my invention I provide an air-discharge chamber which for convenience of construction is shown as comprising a discharge-section 1 and a coupling-section 1^a, connected thereto by screw-threads. The end of the coupling-section farther from the discharge-section is closed by a cap 2, and an air-supply pipe 3, provided with a regulating-valve 3^a and leading from a low-pressure fan-blower, which is not shown, is connected to the coupling-section.

An oil-delivery pipe 4, having an outer end discharge-opening, which is preferably, as shown, a contracted nozzle 4^a, formed by flattening and laterally extending one of its ends, is set centrally within the discharge-chamber 1, the nozzle 4^a being located in or adjoining the delivery or discharge end thereof. The pipe 4 passes through the cap 2 of the chamber and is held in connection thereto in any suitable manner, as by a nut 5 engaging a thread on its periphery and bearing against a

gasket or packing-ring 6, which in turn abuts against the cap and makes a tight joint between the same and the pipe 4. The end of the pipe 4 exterior to the cap 2 is connected to a coupling-socket 7, having a lateral nozzle, to which is connected an oil-supply pipe 8, provided with a suitable regulating cock or valve 8^a and leading from a supply-tank which is located above the burner and is open to the atmosphere. An air-discharge blast-pipe 9, controlled by a cock or valve 9^a, leads from the air-supply pipe 3 to the outer end of the coupling-socket 7.

It will be seen from the foregoing construction and arrangement the inner or delivery pipe 4, nozzle 4^a, and the openings of the coupling-socket 7 are all in one line and form a continuous and unobstructed passage whereby it permits a lower pressure of air to be used than is usual in this class of burners to atomize and force the oil into the oil-delivery pipe of the burner and out of the nozzle. Furthermore and a most important advantage of this construction of an unobstructed passage is that it enables an unskilled person to pass a rod or other cleaning device throughout the entire length of the device from the point where the oil is fed into the burner to the nozzle where the mixed oil and air leave, thus permitting all obstructions to be easily detached and removed.

I have shown in the drawings the common form of elbow 10, connecting the air-pipe 9 to the valve 9^a; but any other common form and well-known construction could be substituted in lieu thereof—as, for example, an elbow provided with a removable plug or plugs, as shown in Fig. 2 of Patent No. 737,903 to Bray, September 1, 1903. The valve 9^a, controlling the air, can be located anywhere in the length of the pipe 9.

In the operation of the appliance oil is delivered by gravity from the supply-tank through the supply-pipe 8 into the delivery-pipe 4 and is forced through the same and out of its discharge-nozzle 4^a by a blast of air at low pressure—as, say, eight ounces—supplied from the fan-blast-supply pipe 3 into the inner end of the oil-delivery pipe 4 through the discharge blast-pipe 9. The current of

mingled oil and air which passes out of the discharge-nozzle meets and is atomized by the blast delivered to the inclosing section 1 of the discharge-chamber. The resultant mixture is ignited and burns with a soft white flame within a clear space in advance of the discharge-nozzle, the degree of heat being regulated as desired by a proper adjustment of the cock which controls the blast-discharge pipe.

Burners of the construction herein set forth have been regularly operated in practical shop service for about nine months last past, using heavy oil of the character produced on the Pacific coast, and have been found to satisfactorily and economically perform their intended function. The flame burns from about twelve inches beyond the discharge-nozzle to the end of a furnace eight feet in length, heating a charge of three thousand pounds of scrap in forty-five minutes, so that it can be worked like bread-dough and penetrating the iron and melting slag and other impurities without a cutting action, which would waste or burn the iron.

I claim as my invention and desire to secure by Letters Patent—

1. In a hydrocarbon-burner, the combination of a free and unobstructed oil-delivery

pipe having an outer end discharge-opening, 30 a surrounding air-discharge chamber, an air-supply pipe leading into the discharge-chamber, an air-discharge blast-pipe connected to the air-supply of the discharge-chamber and having a connection with the inner end of the 35 oil-delivery pipe, an oil-supply pipe leading into and having its end substantially flush with the oil-delivery pipe in advance of the air-discharge blast-pipe.

2. In a hydrocarbon-burner, the combination of an air-discharge chamber, a cap closing one end thereof, a free and unobstructed oil-delivery pipe having an outer end discharge-opening adjoining the open end of the air-discharge chamber and extending therefrom through the cap of the chamber, an air-supply pipe leading into the air-discharge chamber, an air-discharge blast-pipe leading from the air-supply pipe to the inner end of the oil-delivery pipe, a cock or valve controlling the air-discharge blast-pipe, and an oil-supply pipe leading into and having its end substantially flush with the oil-delivery pipe in advance of the air-discharge blast-pipe.
